US00D894213S

(12) **United States Design Patent** (10) Patent No.: **US D894,213 S**
 Doti et al. (45) Date of Patent: **** Aug. 25, 2020**

(54) **DISPLAY SCREEN OR PORTION THEREOF WITH GRAPHICAL USER INTERFACE**

(71) Applicant: **Salesforce.com, Inc.**, San Francisco, CA (US)

(72) Inventors: **Adam McCormick Doti**, Petaluma, CA (US); **Cameron Reynolds-Flatt**, San Francisco, CA (US)

(73) Assignee: **Salesforce.com, Inc.**, San Francisco, CA (US)

(**) Term: **15 Years**

(21) Appl. No.: **29/678,006**

(22) Filed: **Jan. 25, 2019**

(57) **CLAIM**

The ornamental design for a display screen or portion thereof with graphical user interface, as shown and described.

DESCRIPTION

The FIGURE is a front view of a display screen or portion thereof with graphical user interface, showing the claimed design.

The portion of the display screen, text, graphics, and other elements shown in broken lines form no part of the claimed design.

1 Claim, 1 Drawing Sheet
